UNITED STATES PATENT OFFICE

ALBERT O. DENNIS, OF SPRINGFIELD, OHIO, ASSIGNOR TO THE CENTRAL BRASS & FIXTURE COMPANY, OF DAYTON, OHIO, A CORPORATION OF OHIO

APPARATUS AND PROCESS FOR TEMPERING STEEL

Application filed April 20, 1928. Serial No. 271,596.

My invention relates to an apparatus for heating, forming and tempering steel articles.

It is the object of my invention to provide an apparatus for the practice of my process of heating, forming and air cooling by tempered air, preferably below room temperature, of steel articles of high manganese and low carbon content.

10 This application is a co-pending application with Serial #271,595, filed Apr. 20, 1928.

Referring to the drawings:

Figure 1 is a top plan view of the apparatus I employ;

15 Figure 2 is a side elevation thereof.

Referring to the drawings in detail, 1 is a furnace, of which there may be a plurality. Each furnace is adjacent to a table 6. The table 6 is for the purpose of supporting the 20 heated steel strips, such as used for bumper bars for automobiles, on their way to the press or forge 5 where they are suitably formed while still hot.

These hot formed articles are then placed 25 upon an endless conveyor 3 and passed beneath an air blast furnished by the fan 4 through the passageways 4^a and 4^b. The air is tempered by the water sprays 9^a from the water pipes 9. Surplus moisture is removed 30 by the scrubbing plates 8.

The strips are cooled by this air blast; the stronger the blast and the greater the proportion of moisture, the harder the steel will be. The cooled strips are passed through the 35 air blast on the conveyor 3 and thence on the transverse conveyor 7 to a point of assembly.

The steel employed is preferably that having a manganese content of from .9 percent to 2 1/2 percent, and a carbon content of from 40 .3 percent to 1 percent. Phosphorous, silicon and sulphur contents are maintained at a minimum, such as .9 percent for phosphorous, .3 percent for silicon and .6 percent for sulphur. Heretofore, in the making of bumper 45 bars, for instance, the steps of heating, forming, cooling, heating again to quenching temperature, quenching in oil, drawing while hot up to the critical temperature of the steel and straightening when cold, were all necessary 50 steps. With my apparatus, these steps are

reduced to the heating and forming operation while hot and the cooling, preferably, by the air blast. This economizes not only in equipment, labor, costs and time consumed, but also in the loss due to imperfect heat treating 55 of the steel.

Heretofore, it has been impossible to secure a uniform quenching and tempering of the steel. Certain irregularities due to irregularities of temperatures in the oil and other causes made it difficult to get full production 60 without heavy losses.

It will be understood that I desire to comprehend within my invention such modifications as may be necessary to adapt it to varying 65 conditions and uses.

Having thus fully described my invention, what I claim as new and desire to secure by Letters Patent, is:

In a bar-tempering apparatus, means for 70 forming and directing a stream of air, means for injecting sprays of water into said stream, means for removing the surplus of water from said air stream, and means for directing said stream onto said bars.

75 In testimony whereof, I affix my signature.
ALBERT O. DENNIS.
